(57) **CLAIM**

The ornamental design for a hinged dock ramp, as shown and described.

DESCRIPTION

FIG. 1 is a perspective view of a hinged dock ramp;
FIG. 2 is a side view of the hinged dock ramp of FIG. 1;
FIG. 3 is another side view of the hinged dock ramp of FIG. 1;
FIG. 4 is a front view of the hinged dock ramp of FIG. 1;
FIG. 5 is a back view of the hinged dock ramp of FIG. 1; and,
FIG. 6 is a top view of the hinged dock ramp of FIG. 1.
The dashed lines are provided for illustrative purposes only
and form no part of the claimed design.
